COMBER

Benjamin Bailey, Boston, Mass., assignor to Alsatian Machine Werks, Limited, Boston, Mass., a corporation of Massachusetts

Application December 12, 1933, Serial No. 702,000

14 Claims. (Cl. 19—118)

The invention relates especially to that type of comber in which a nipper moving forward and backward has associated with it a pair of detaching rolls which assist in detaching a combed tuft of fibres from the lap borne by the nipper and piecing it to the end of the web already combed. During this operation the detaching rolls have a progressive forward and reverse movement. The forward movement of the rolls assists in the detachment of the combed tuft from the lap at the same time effecting the piecing up operation and advancing the combed web in a determinate amount. The reverse movement of the detaching rolls, then following, re- turns the combed web for its end to receive the combed fringe of lap laid upon it by the forward movement of the nipper preliminary to the next piecing up operation.

Difficulties are encountered in the effective operation of the comber in accordance with the principles above outlined in that the body of the combed web is oftentimes not uniform in thickness and curled strands of fibre appear in it, these differences being aggravated more or less by the character of the staple worked upon.

The difficulties above referred to arise primarily from the character of the combed tuft detached from the lap and added to the end of the combed web. This tuft presents a body portion in thickness substantially equal to the thickness of the combed web. As approach is made to the free front and rear ends of the tuft, however, the thickness of the tuft is gradually lessened, the extreme free ends of the tuft both terminating in finely drawn out filaments.

Accordingly in order to obtain substantial uniformity in the thickness of the combed web the contracted fore end portion of the tuft should be applied and pieced to the contracted rear end portion of the combed web which is the contracted rear end portion of the tuft last applied.

Curls occur in some of the fibres of the combed web for the reason that after piecing up operation the detaching rolls advance the combed web so far that the contracted rear end of the tuft last pieced to the web is brought into the bite of the rolls, sometimes only a relatively few filaments of the fibres remaining between the rolls. In consequence upon the reverse movement of the rolls, the top roll having been moved back over the bottom roll in the operation of the machine, the fibres left between the rolls will tend to follow the top roll and curl around it. Accordingly when the detaching rolls are again advanced curls will appear in the combed web. This

difficulty I have found may be overcome if at the termination of the forward movement of the detaching rolls the body of the web is left in the bite of the rolls. Accordingly for overcoming this difficulty of curls in the combed web as well as for obtaining such piecing up as will effect uniformity of thickness in the body of the web, it is necessary that the detaching rolls have a precise forward and reverse movement properly related, and that the movements shall vary dependent upon the character of staple worked upon.

The objects of my invention are accordingly as follows:

1. That the machine may deliver a combed web or sliver having uniformity of body.
2. That the fibres in the combed web or sliver thus delivered shall be free from curls.
3. That a precise forward and reverse movement shall be given the detaching rolls and in timed relationship to the other operating parts of the machine.

4. That an unnecessary excess motion in the detaching rolls shall be eliminated and to this extent preventing wear upon the rolls, especially the leather covered top roll.

5. That both the forward and reverse movement given the detaching rolls shall be a precisely adjusted movement, and in which the relative extent of movement forward and reverse shall be evident to the operator by an indicator.

For purposes of illustration the invention is described as applied to a comber shown in the Tunstall Patents No. 1,351,076 of August 13, 1920 and No. 1,394,054 of October 18, 1921, such portions only of the machine being shown as are necessary for a proper understanding of the invention.

In the drawings:

Fig. 1 is a front elevation of certain of the detaching rolls and mechanism for controlling the operation of these rolls.

Fig. 2 is a section on line 2—2 of Fig. 1.

Fig. 3 is a section on line 3—3 of Fig. 1.

Fig. 4 is a longitudinal section of the roller motion forming a part of the operating mechanism.

Fig. 5 shows the mechanism in side elevation.

Fig. 6 is a plan of the mechanism.

Fig. 7 shows in perspective a portion of the mechanism to which especial attention will later be directed.

Figs. 8 to 11, inclusive, show diagrammatically the positions assumed by certain parts of the mechanism during the operation of the machine; and

Fig. 12 shows in cross section a detail of construction.

1 and 2 are the front bottom and top detaching rollers, respectively. 3 and 4 are the back bottom and top detaching rollers, respectively. The back top detaching roller 4 is moved forward and backward around the axis of the back bottom roller 3 in the usual manner during the operation of the machine by mechanism not shown. 10 The rollers are suitably supported in bearings on the machine.

The front and back bottom detaching rollers 1 and 3 are driven rollers, the roller 1 having a pinion 5 on its driven end, the roller 3 having a pinion 6 on its driven end. These pinions are in mesh with an idler 7. In mesh with the pinion 6 is a gear 8 for driving the rollers 3. The motion thus applied to the pinion 6 by the gear is transmitted to the pinion 5 for driving the roller 20 1 by the idler 7. Thus both rollers 1 and 3 will be operated by the gear 8 to turn simultaneously in the same direction.

The gear 8 is turned by a roller motion 9. This motion is driven by a stud 10 in a revolving disk 25 11 through a rigid connecting link 12. The disk 11 is arranged upon a shaft 13 having bearing to turn on an upright 15 forming a part of the frame of the machine. The shaft 13 is turned by a gear 16. This gear is constantly in mesh 30 through intermediate gearing, not shown, with the main driving shaft of the machine, and accordingly through mechanism, not shown, may receive a change in timing with relation to the rest of the machine.

35 The roller motion 9 comprises spaced cheeks 18, 19 rigidly connected by pins 20. Arranged within the cage formed by these cheeks, and mounted to turn on a shaft 22, is a ratchet 23 having a hub 24 to which the gear 8 is keyed. The cheek 18 is 40 mounted to turn freely upon this same hub. Arranged also within the cage formed by the cheeks and mounted on the shaft 22 is a pawl controlling disk 25 having a hub 26 upon which the cheek 19 is mounted to turn freely. The hub 26 is 45 keyed to the shaft 22. Pivotaly mounted on one of the pins 20 connecting the cheeks is a pawl 27 (see Fig. 5) having a toothed end 28 for engaging and operating the ratchet. In this connection it will be noted that the pawl bears squared teeth 50 adapted to fit into similarly squared indentations or apertures in the periphery of the ratchet by which means the pawl will be enabled to move the ratchet in reverse directions when in engagement therewith. The toothed end of the pawl also 55 preferably bears a plurality of teeth for engaging the ratchet in order that a maximum amount of strength may be secured between the teeth on the pawl and the notched end of the ratchet but still enabling the notches in the ratchet to be 60 made relatively near together so securing quick engagement between the pawl and ratchet when the pawl is allowed to have engagement therewith. Fixedly connected to the pawl is an arm 29 bearing upon its end a wheeled follower 30 65 arranged to have bearing against the peripheral edge of the pawl adjusting disk 25. This disk presents edge surfaces 31 and 32 located at different distances radially from the axial center of the disk or so that when the follower 30 is in 70 engagement with the edge surface 31 of the disk the toothed end of the pawl will be lifted out of engagement with the ratchet, and when the follower is in engagement with the edge surface 32 of the disk the pawl will be allowed to have engagement with the ratchet for operating it. The 75

follower 30 is maintained in constant engagement with the peripheral edge of the disk 25 by a spring 33 coiled upon the pin on which the pawl is mounted with one end fixed to one of the cheeks and the other end of the spring bearing against 5 the arm 29 carrying the follower.

With the parts of the roller motion thus arranged the ratchet 23 will be moved by the pawl in reverse directions. The direction of such movement will depend upon the direction of oscillatory movement given the cage by the operation of the driving disk 11 through the connecting link 12. The time and extent of such movement will depend upon the turned, located position of the pawl adjusting disk 25 which allows 15 the teeth of the pawl to have engagement with the ratchet or lifts them into a disengaging position with relation to it. The driving disk 11 located below the roller motion, and continuously turning in a clockwise direction as indicated by 20 the arrow thereon, imparts to the link 12 a reciprocatory up and down movement and the end of the link is pivotally connected by a pin 34 to the cheeks of the cage in manner whereby as the link moves upwardly the cage will be turned 25 in a clockwise direction, and as the link moves downwardly the cage will be turned in a reverse or anti-clockwise direction.

As explained above, the time and extent of movement of the ratchet in either direction will 30 depend in part upon the turned position of the pawl adjusting disk 25. For turning the disk and thereby positioning it an arm 35 is arranged upon the end of the shaft 22 to which the hub 26 of the disk is keyed. This arm extends upwardly 35 at right angles to the shaft. The precise direction and extent of movement given the disk 25 at any timed interval, the time of such movement, and the stationary located position of the disk at the termination of such movement for any interval of time will depend upon the control of the arm 35 fixedly coupled as it is to the disk through the shaft and intervening hub.

Connecting with the arm 35 is a sliding carriage 36 having as its fore end portion an arm 45 37 and back of this arm a forked rear end portion 37'. The forward end of the arm 37 is pivotally but fixedly secured to the arm 35 at any one of a variety of adjusted positions away from the inner end of the arm or axis of the shaft 50 22 on which the arm is mounted. To this end the arm 35 has a longitudinal slot 38 in it and the end of the arm 37 connects with the arm 35 by means of a fastening clamp 39 passing through this slot when the two arms become pivotally 55 connected on tightening the clamp. The arm 37 is made in separate parts 40 and 41 with end portions lapping by one another and slidably fitted one to the other by a tongue 42 on one part fitting within a groove 43 in the other part in order 60 that the arm may be lengthened or shortened. The overlapping portions of the respective parts of the arm are provided with a longitudinal slot 44 and passed through this slot is a clamping stud 45 which, when tightened, locks together 65 the separate parts of the arm in any adjusted position for lengthening or shortening it. In order that the lengthening or shortening of the arm 37 may be obtained with an exact nicety the part 40 of the arm is provided upon its side with 70 a stud 46 within which is arranged to turn an adjusting screw 47 which enters a stud 48 formed on the side of the other part 41 of the arm 37 or side of the carriage 36. By turning this screw with forward or reverse movement the precise 75

adjustment of the arm as to length is secured after which the separate parts of the arm may be locked together on tightening the clamp stud 45 as aforesaid. The forked rear end portion 37¹ of the carriage 36 extends inwardly to embrace and slide upon a sleeve 50 loosely arranged upon a rotary shaft 51. This sleeve is provided at either side with annular flanges 52 against which the fork bears laterally and is thereby prevented from lateral displacement as it slides upon the sleeve. Fixedly secured to the shaft 51 alongside the sleeve 50 is an eccentric 53 presenting a fore end portion 54 the extremity of which has considerable extension from the center of the shaft 51 on which the eccentric is mounted, and a rear end portion 55 the extremity of which has relatively but little extension from the center of the shaft on which the eccentric is mounted. Located forward of the eccentric on the side of the carriage is a wheel 56 with which the eccentric has engagement. The carriage 36 is maintained in a normally retracted position by means of a spring 57 in consequence of which, as the eccentric is turned by the rotation of the shaft 51, the carriage 36 and arm 35 to which the end of the carriage is secured will be moved forward as the fore end portion 54 of the eccentric is turned to engage the wheel on the carriage, and the carriage and arm then moved back by the action of the spring 30 until the wheel on the carriage engages the end portion 55 of the eccentric acting as a stop for defining the retracted position of the carriage and arm. In other words, the arrangement is such that the carriage 36 and arm 35 moved by it will be reciprocated as the eccentric is turned by the turning of the shaft 51 on which the eccentric is mounted. Arrangement is made whereby the return movement of the carriage obtained by the action of the spring 57 may be shortened before the wheel 56 on the carriage engages the extremity of the end portion 55 of the eccentric during the turning thereof, this by a screw 58 on the side of the carriage which engages a stop 59 on the upright 15.

45 The rotary shaft 51 on which the eccentric 53 is mounted has bearing to turn on the upright 15 and is turned in timed relation to the rest of the machine by a gear 61 on said shaft, which is one of the gears of the machine operating other parts 50 and is itself turned by gearing from the main shaft.

55 The outer end of the arm 35 forming a pointer moves across the face of an indicator 63 having a scale 64 with indications running in opposite directions from a common center. The indicator is fixed to the upright 15. The indicator according to the indication on the scale as designated by the pointer indicates the relative movement in reverse directions of the arm 35 and accordingly that of the pawl controlling disk 25 which has the same movement as the arm. The zero point on the scale and from which the scale runs in opposite directions is an assumed point about half way between the extremes of movement in forward and reverse directions of the arm.

70 The mechanism above described is applicable to a double sided comber as well as a single sided comber. In the case of the double sided comber there will be two of the gears 61 in mesh arranged on separate shafts 51 and turning in reverse directions and accordingly the mechanisms operated by them respectively will be operating in reverse directions one to the other. 75 In the case also of the double sided comber the

spring 57 which effects a return of the carriage upon the termination of its forward movement by the eccentric is interposed between and attached to separate carriages 36 on the respective sides of the comber as shown in Fig. 5.

5 The operation is as follows: The rotation of the driving disk 11 will impart through the link 12 a forward and reverse oscillatory movement to the cage which carries the pawl 27 for operating the ratchet 23. The cage is turned forward in a clockwise direction as the link moves upwardly, and in a reverse or anti-clockwise direction as the link moves downwardly. As the link moves downwardly, assuming the pawl is in engagement with the ratchet the ratchet will be turned in an anti-clockwise direction the same as the cage, thereby turning the gear 8 mounted on the hub of the cage in the same anti-clockwise direction. The gear 8 in turn will through the pinion 6, idler 7 and pinion 5 turn the front 20 and back bottom detaching rollers 1 and 3 in a forward direction or in a direction to deliver or feed the combed web or sliver then lying between these rollers and their co-operating top rollers. On the termination of the downward 25 movement of the link 12 the continued operation of the driving disk will move the link upwardly thereupon reversing the movement of the cage to move in a clockwise direction, and, assuming the pawl to be in engagement with the 30 ratchet, the gear 8 through the pinions and idler above referred to will reverse the movements of the rollers causing them to turn back any combed web or sliver then lying between them.

35 As the cage of the roller motion is moved forward and back, operating the detaching rollers, the direction, time and extent of their movement will depend upon the direction of movement of the cage of the roller motion, and upon the time and period of engagement of the pawl with the 40 ratchet, and this will depend upon the position of the pawl controlling disk 25 which permits engagement or disengagement of the pawl with relation to the ratchet. The relative positions of the pawl controlling disk and follower 45 during each period of the forward and reverse movements of the detaching rollers is shown diagrammatically in Figs. 8 to 11, inclusive. Fig. 8 illustrates the relative positions of the pawl controlling disk and follower at 50 the beginning of the forward movement of the detaching rollers. The driving disk 11 is now about to move the cage of the roller motion backward or in an anticlockwise direction. The follower is engaging the edge 32 of the pawl 55 controlling disk and the pawl is in engagement with the ratchet. Thereupon as the cage is moved backward the follower will travel along the edge 32 of the disk permitting the feed of the detaching rollers until the follower rides up 60 onto the edge 31 of the disk thereby throwing out the pawl and preventing further feed of the detaching rollers. After the follower rides up onto the edge 31 of the disk it will continue its movement along this edge until the termination of the reverse movement of the cage of the roller motion and will assume a position substantially as shown in Fig. 9. The feed of the detaching rollers may continue for the whole or any part of the reverse movement of the cage 70 of the roller motion and will depend upon the precise adjusted position of the pawl controlling disk, the position of the disk controlling the time when the roller rides off the surface 32 onto the surface 31 of the disk. After the cage of the 75

roller motion has concluded its reverse movement the driving disk will thereupon move the cage in a forward or clockwise direction, the disk and follower being then substantially in the 5 position shown in Fig. 9. At just about the instant of the beginning of this forward motion of the cage the disk will be turned into a position substantially as shown in Fig. 10, the follower then resting on the edge 31 of the disk 10 and the pawl accordingly being out of engagement with the ratchet. Thereupon as the forward motion of the cage continues the follower will move along the edge 31 of the disk until it rides down onto its edge 32 permitting engagement 15 between the pawl and ratchet and thereby moving the detaching rollers in a reverse direction, the movement continuing until the termination of the forward movement of the cage when the follower will be left in engagement with 20 the edge 32 of the disk and occupying a position substantially as shown in Fig. 11. The extent of the reverse movement of the detaching rollers will depend upon the precise adjusted position of the pawl controlling disk or, in other 25 words, upon the time when the follower will ride onto its edge 32. As just described, at the termination of the forward movement of the cage and reverse movement of the detaching rollers, the follower will be left engaging the edge 32 of 30 the disk and accordingly the pawl in engagement with the ratchet. Thereupon at just about the instant that the cage is moved backward, the follower then being in the position shown in Fig. 35 11, the pawl adjusting disk will be moved back into the position shown in Fig. 8, when the operation will be repeated.

It will accordingly be seen that the time and exact extent of the forward and reverse movements of the detaching rollers for any period of 40 operation will depend upon the turning and precise adjusted position for any interval of time of the pawl controlling disk.

The change in the relative position of the pawl controlling disk and the location of said disk at 45 timed intervals is obtained by the eccentric 53 and spring 57 in their combined influence upon the sliding carriage 36 which, through their engagement with the arm 35, controls the movement and located position of the pawl controlling disk. As the eccentric is turned by the shaft 51 the end portion 54 of the eccentric will be turned to engage the wheel 56 on the carriage whereupon the carriage will be moved forward moving the arm 35 into a reverse position as 55 shown on the indicator 63 and moving the pawl controlling disk from a position as shown in Fig. 10 into the position shown in Fig. 9 preparatory to the imparting of a reverse movement to the detaching rollers as above described. The extent of such movement of the detaching rollers 60 will depend upon the distance that the pawl controlling disk is turned as determined by the throw of the arm 35 as indicated upon the scale 64 of the indicator, the extent of such movement of the arm being determined by the throw of the forward end portion 54 of the eccentric and 65 adjustments as will later be referred to.

As the forward end portion 54 of the eccentric turns away from the wheel 56 on the carriage 70 the spring 57 will act through the carriage to move the arm into a delivery position as shown on the indicator, thereby moving the pawl controlling disk from a position as shown in Fig. 11 into the position shown in Fig. 8 preparatory 75 to the imparting of a delivery or feed movement

to the detaching rollers as above described. The extent of such feed will depend upon the distance that the pawl controlling disk is turned, or upon the distance that the arm 35 is turned into its 5 delivery position as indicated upon the scale of the indicator and this is determined by the amount that the spring is allowed to draw back the carriage, the limit of such movement being determined either by the engagement of the wheel on the carriage with the end portion 55 of the eccentric, or by the engagement of the adjusting screw 58 on the carriage with the butt 59 forming a stop on the frame of the machine.

By means of the adjustments the exact and precise extent of movement of the arm 35 in the 15 direction of delivery or reversal as shown on the indicator and accordingly the exact and precise extent of movement of the pawl controlling disk, which measures the extent of feed of the detaching rollers and the extent of their reverse 20 movement, will be obtained. These adjustments include the adjustable connection 39 between the arm 37 of the carriage and the arm 35, the adjusting screw 47 for shortening or lengthening the arm 37 of the carriage coupled 25 with the clamp stud 45 for locking together the separate parts of this arm in any adjusted position, and the adjusting screw 58 on the carriage which by its engagement with the butt on the frame of the machine acting as a stop limits the 30 reverse movement of the carriage as effected by the spring. By connecting the arm 37 of the carriage to the arm 35 at points variably distant from the axial center of the shaft on which this arm is mounted, or by lengthening or shortening 35 the arm 37 of the carriage great variety in the extent of movement of the arm 35 on the reversal side of the indicator may be obtained, while the exact extent of movement of the arm on the delivery side of the indicator may be obtained through adjustment of the screw 58 which 40 engages the butt on the frame acting as a stop. In fact any precise adjustment in the throw of the arm 35 as on the delivery and reverse side on the indicator as evidenced by its scale 45 may be obtained through some one or all the adjustments above noted, and accordingly the precise extent of feed of the detaching rollers occurring at properly timed intervals is also obtained, inasmuch as the pawl controlling disk 50 which controls the operation of these rollers is itself controlled by the movement and positioning of the arm 35.

With the mechanism thus provided any varying extent of forward and reverse movement 55 may be imparted to the detaching rollers, depending upon the character of the staple worked upon. For obtaining the piecing up operation and delivering the combed web the feed of the rollers will progress so far as to obtain a maximum feed or delivery, at the same time not so far but that the body of the web will be left in the bite of the rear detaching rollers. Consequently on the reverse movement of the rollers for returning the web for obtaining the piecing up 65 operation, the fibres in the combed web will not follow the top roller and accordingly curls in the combed web will be eliminated. The reverse movement of the detaching rollers will only be so far as to properly effect the piecing up 70 operation for obtaining a web of uniform body. In other words, the reverse movement of the rollers will be so graduated as to make such return of the web that the combed fringe of the lap brought forward by the nipper for effecting the 75

piecing up operation will be applied and pieced to the contracted rear end portion of the combed web, which is the contracted rear end portion of the tuft last applied, and will not be laid to 5 lap onto the body of the web. Consequently there will be delivered a combed web or sliver having uniformity of body. All excess motion in the detaching rollers will be eliminated so preventing wear. Not only is the forward and reverse movement given the detaching rollers a precisely adjusted movement but is obtained by adjustment inherent in the machine without renewal of replacement of parts and with the relative extent of movement forward and reverse 10 clearly obvious to the operator as evidenced by the scale on the indicator.

Having thus fully described my invention, I claim and desire to secure by Letters Patent of the United States:

20 1. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling 25 the engaging or disengaging position of said clutch element depending upon the position of said controlling member, and the position of which controlling member is changed in reverse direction in a determinate amount during each 30 cycle of forward and reverse movement of said oscillatory member whereby a determinate period of engagement will be permitted the clutch element with the clutch body during both the forward and reverse movements of said oscillatory member.

2. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling the engaging or disengaging position of said clutch element depending upon the position of said controlling member, and the position of which controlling member is changed in reverse 45 directions in a determinate amount during each cycle of forward and reverse movement of said oscillatory member whereby a determinate period of engagement will be permitted the clutch element with the clutch body during both the forward and reverse movements of said oscillatory member, and means whereby the change of position of said controlling member may be adjustably varied for varying the extent of both the forward and reverse rotation movements of 50 said roll.

3. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling the en- 55

gaging or disengaging position of said clutch element depending upon the position of said controlling member, and the position of which controlling member is changed in reverse directions in a determinate amount during each cycle of forward and reverse movement of 60 said oscillatory member.

4. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling 65 the engaging or disengaging position of said clutch element depending upon the position of said controlling member, and the position of which controlling member is changed in reverse directions in a determinate amount during each cycle of forward and reverse movement of said oscillatory member, and means for changing the position of said controlling member by movement thereof in reverse directions in a determinate amount during each cycle of forward and reverse movement of 70 said oscillatory member.

5. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling the engaging or disengaging position of said clutch element depending upon the position of said controlling member, and the position of which controlling member is changed in reverse directions in a determinate amount during each cycle of forward and reverse movements of said oscillatory member whereby a determinate period of engagement will be permitted the clutch element with the clutch body during both the forward and reverse movements of said oscillatory member, an arm connecting with said controlling member for reversely turning it as the arm is moved alternately in reverse directions, and means for moving said arm alternately in reverse directions during each cycle of forward and reverse movement of said oscillatory member.

6. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be op- 75

erated thereby and having an engaging or disengaging position with relation to the clutch body, and a controlling member for controlling the engaging or disengaging position of said clutch element depending upon the position of said controlling member, and the position of which controlling member is changed in reverse directions in a determinate amount during each cycle of forward and reverse movements of said oscillatory member whereby a determinate period of engagement will be permitted the clutch element with the clutch body during both the forward and reverse movements of said oscillatory member, an arm connecting with said controlling member for reversely turning it as the arm is moved alternately in reverse directions, means for moving said arm alternately in reverse directions during each cycle of forward and reverse movement of said oscillatory member, and adjustable means whereby variance may be obtained in the extent of movement of said arm.

7. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling the engaging or disengaging position of said clutch element depending upon the position of said controlling member, and the position of which controlling member is changed in reverse directions in a determinate amount during each cycle of forward and reverse movements of said oscillatory member whereby a determinate period of engagement will be permitted the clutch element with the clutch body during both the forward and reverse movements of said oscillatory member, an arm connecting with said controlling member for reversely turning it as the arm is moved alternately in reverse directions, means for moving said arm alternately in reverse directions during each cycle of forward and reverse movement of said oscillatory member, and adjustable means whereby variance may be obtained in the limit of both the forward and reverse movements of said arm.

8. In a combing machine having a detaching mechanism including a roll, mechanism for imparting determinate alternate forward and reverse movements to said roll including, an oscillatory member, means for oscillating said member, a clutch having a movable clutch element connected to said oscillatory member to be operated thereby and having an engaging or disengaging position with relation to the clutch body, and a controlling member for controlling the engaging or disengaging position of said clutch element depending upon the position of said controlling member, and the position of which controlling member is changed in reverse directions in a determinate amount during each cycle of forward and reverse movements of said oscillatory member whereby a determinate period of engagement will be permitted the clutch element with the clutch body during both the forward and reverse movements of said oscillatory member, an arm connecting with said controlling member for reversely turning it as the arm is moved alternately in reverse directions, means for moving said arm alternately in reverse directions during each cycle of forward and reverse movement of

said oscillatory member, adjustable means whereby variance may be obtained in the limit of both the forward and reverse movements of said arm, and an indicator with which the end of said arm co-operates for showing the limit of both its forward and reverse movements.

9. The combination comprising an oscillatory member with means for oscillating said member, of mechanism for transmitting the motion of said member in opposite directions for each cycle of forward and reverse movements of said oscillating member and in a determinate amount for either of said directions, said mechanism including, a clutch having a movable clutch element connected to said oscillatory member to be operated thereby and having an engaging or disengaging position with relation to the clutch body, and a controlling member for controlling the engaging or disengaging position of said clutch element depending upon the positioning of said controlling member, and the position of which controlling member is changed in reverse directions in a determinate amount during each cycle of forward and reverse movement of said oscillatory member whereby determinate periods of engagement will be permitted the clutch element with the clutch body during both the forward and reverse movement of said oscillatory member.

10. The combination comprising an oscillatory member with means for oscillating said member, of mechanism for transmitting the motion of said member in opposite directions for each cycle of forward and reverse movements of said oscillating member and in a determinate amount for either of said directions, said mechanism including, a clutch having a movable clutch element connected to said oscillatory member to be operated thereby and having an engaging or disengaging position with relation to the clutch body, and a controlling member for controlling the engaging or disengaging position of said clutch element depending upon the positioning of said controlling member, and the position of which controlling member is changed in reverse directions in a determinate amount during each cycle of forward and reverse movement of said oscillatory member whereby determinate periods of engagement will be permitted the clutch element with the clutch body during both the forward and reverse movement of said oscillatory member, and means whereby the extent of movement of said controlling member in either direction may be adjustably varied.

11. The combination comprising an oscillatory member with means for oscillating said member, of mechanism for transmitting the motion of said member in opposite directions for each cycle of forward and reverse movements of said oscillating member and in a determinate amount for either of said directions, said mechanism including, a clutch having a movable clutch element connected to said oscillatory member to be operated thereby and having an engaging or disengaging position with relation to the clutch body, and a controlling member for controlling the engaging or disengaging position of said clutch element depending upon the positioning of said controlling member, and the position of which controlling member is changed in reverse directions in a determinate amount during each cycle of forward and reverse movement of said oscillatory member whereby determinate periods of engagement will be permitted the clutch element with the clutch body during both the forward and reverse movement of said oscillatory member.

member, and means whereby the position of said controlling member is changed in reverse directions as aforesaid.

12. The combination comprising an oscillatory member with means for oscillating said member, of mechanism for transmitting the motion of said member in opposite directions for each cycle of forward and reverse movements of said oscillating member and in a determinate amount for either of said directions, said mechanism including, a clutch having a movable clutch element connected to said oscillatory member to be operated thereby and having an engaging or disengaging position with relation to the clutch body, a controlling member for controlling the engaging or disengaging position of said clutch element depending upon the positioning of said controlling member, and the position of which controlling member is changed in reverse directions in a determinate amount during each cycle of forward and reverse movement of said oscillatory member whereby determinate periods of engagement will be permitted the clutch element with the clutch body during both the forward and reverse movement of said oscillatory member, means whereby the position of said controlling member is changed in reverse directions as aforesaid, and means whereby the extent of movement of said controlling member in either direction may be adjustably varied.
13. In a combing machine having a detaching mechanism including a roll, mechanism for imparting alternate forward and reverse movements to said roll including, an oscillatory member, means for operating said member to oscillate with determinate forward and reverse movements in a determinate time, and means whereby the motion imparted by said oscillatory member to said roll for imparting forward movement thereto may be stopped at a determinate point short of the

complete movement of said oscillatory member in one direction and whereby, also, the motion imparted by said oscillatory member to said roll for imparting reverse movement thereto may be started at a determinate point short of the complete movement of said oscillatory member in a reverse direction. 5

14. In a combing machine having a detaching mechanism including a roll, mechanism for imparting alternate forward and reverse movements to said roll including, an oscillatory member, means for operating said member to oscillate with determinate forward and reverse movements and in a determinate time, a clutch having a movable clutch element connected to said oscillatory member to be operated thereby and having an engaging or disengaging position with relation to the clutch body, and a controlling member for controlling the engaging or disengaging position of said clutch element depending upon the position of said controlling member, and the position of which controlling member is changed in reverse direction in a determinate amount during each cycle of forward and reverse movement of said oscillatory member whereby the motion imparted by said oscillatory member to said roll for imparting forward movement thereto will be stopped at a determinate point short of the complete movement of said oscillatory member in one direction and whereby, also, the motion imparted by said oscillatory member to said roll for imparting reverse movement thereto will be started at a determinate point short of the complete movement of said oscillatory member in a reverse direction, and means whereby the change of position of said controlling member may be adjustably varied for varying the extent of both the forward and reverse rotation movements of said roll. 20 25 30 35
